UNITED STATES PATENT OFFICE

FERDINAND BUCHHOLTZ, OF KEYSTONE, WISCONSIN

ADJUSTABLE CHIMNEY CLEANER

Application filed October 25, 1927. Serial No. 228,628.

This invention relates to the class of flue cleaners which are adjustable and designed most especially for sweeping chimneys to clear them of soot and other deposits to obviate danger from fire and prevent interference with the draft.

While the drawing illustrates a preferred embodiment of the invention it is to be understood that in adapting the means to meet specific needs and requirements the design may be varied and such other changes in the minor details of construction may be resorted to within the scope of the invention as claimed without departing from the spirit thereof.

For a full understanding of the invention and the merits thereof, reference is to be had to the following description and the drawing heretofore attached, in which,—

20 Figure 1 is a perspective view of an adjustable chimney cleaner embodying the invention.

Figure 2 is an enlarged fragmentary sectional view.

25 Figure 3 is a perspective view of cooperating spiders and an end portion of the spring guide, the parts being separated and disposed in a group.

Corresponding and like parts are referred 30 to in the following description and designated in the several views of the drawing by like reference characters.

The device comprises a centrally disposed rod 1 which is uniformly threaded throughout its length and formed into an eye 2 at its upper end. A spider 3 is mounted centrally upon the rod 1 which is threaded in an opening formed in the center of the spider. Cross heads 4 are provided at the outer ends of the 40 arms of the spider, and pins 5 project outwardly from the ends of the arms.

Flat springs 6 are adapted to be connected intermediate their ends to selected cross heads 4 of the spider, preferably by means 45 of thumb screws 7 which are threaded into openings formed centrally of the cross heads 4. Each of the flat springs 6 is formed with openings to receive the projecting ends of the pins 5 whereby to prevent turning of the 50 springs upon the screws 7. Brushes 8 are

fitted to the ends of each of the springs 6. The brushes 8 may be of any desired construction and secured to the ends of the springs 6 in any manner. It will be understood that the springs 6 are oppositely arranged so that the brushes carried thereby will operate upon opposite walls of a chimney according to the relative position of the cleaner when introduced into the chimney.

55 A spring guide or runner 9 is located intermediate the flat springs 6 to engage one of the walls of the chimney intermediate those engaged by opposite brushes 8. Upon turning the cleaner the brushes 8 will operate upon the walls intermediate thereof. The

runner or guide 9 consists of a flat spring bent approximately into the form of a bow and having its end portions rebent as indicated at 10, then bent laterally as indicated at 11, and longitudinally slotted to receive thumb 60 screws 12, whereby they are adjustably connected to spreaders mounted upon end portions of the rod 1. There are two spreaders at each end of the rod 1, and each of the spreaders comprises two members 13 and 14 which 65 are connected by means of the thumb screws 15. The member 13 is of disk form, whereas the member 14 is elongated. The members 13 are threaded upon opposite ends of the rod 1 and are adjusted towards and away 70 from the spider 3 by rotation to the right or to the left, as required. When the spreaders are moved towards the spider the outer ends of the springs 6 are deflected outwardly, thereby separating opposite brushes 8 and 75 adapting the cleaner for larger chimneys. Outward movement of the spreaders towards the ends of the rod 1 admits of the outer ends of the springs 6 moving inward, whereby the cleaner is adapted for chimneys of smaller 80 size. Movement of the spreaders along the rod 1 brings the offset ends 11 of the spring runner or guide 9 closer together or farther apart, with the result that the outer portion of the runner or guide is moved outwardly 85 or inwardly to correspond with the adjustment of the brushes. Each of the spreaders comprises the members 13 and 14. The member 14 has a slot formed therein through which 90 the threaded rod 1 loosely passes, but said 100

95 member 14 is held in place by the thumb screws 12.

member has the guide 9 adjustably connected thereto by means of the screw 12. Adjustment of the spreaders on the rod 1 is effected by rotating the members 13 to the right or to the left, according to the desired adjustment and when the members 13 are adjusted, the members 14 are connected thereto by means of the screws 15.

Short chains 16 are connected at one end 10 to the upper ends of the springs 6. A third chain 17 is connected to the upper end of the guide 9. The upper ends of the chains 16 and 17 converge and are connected to an operating chain 19 or like part by means of a 15 ring 20. The chain 17 is adjustably connected with the ring 20, and its upper end has a snap hook fitted thereto which is adapted to engage a link of the chain 17.

The spider 3 includes two arms which cross 20 at a right angle. One arm is short and the other arm long. The cross heads 4 at the ends of the respective arms of the spider are equidistant from the rod 1. The springs 6 may be attached to the cross heads 4 of either set 25 of arms of the spider according to the size of the chimney to be cleaned. For small sized chimneys the guide 9 may be omitted and the springs 6 may be attached to the cross heads 4 of the short arm of the spider. The 30 spiders 14 may likewise be dispensed with. For larger chimneys the spiders 14 are required to deflect the ends of the springs 6 outwardly to spread the brushes 8 the requisite distance to engage opposite walls of the chimney 35 when the cleaner is in active operation. When the walls of the chimney are of a width greater than the length of the brushes the guide 9 properly positions the cleaner to act upon a portion of the walls, the remaining 40 portion being cleaned by turning the cleaner, as will be readily comprehended. By adjusting the guide 9 and the spreaders the cleaner may be readily adapted for different sized chimneys.

45 Having thus described the invention, I claim:

1. A chimney cleaner comprising a rod, flat springs connected intermediate their ends to the said rod and provided at opposite ends 50 with brushes, spreaders adjustable on the rod and engaged between the springs for spreading the same, and a spring guide of bow form having its ends adjustably connected with the spreaders and movable therewith.

55 2. A chimney cleaner comprising a rod, supporting elements upon opposite end portions of the rod, cleaning members mounted upon the rod and a spring guide of bow-form having opposite end portions rebent, thence 60 out-turned and slotted, the slotted portion engaging the supporting elements and adjustably connected thereto.

65 3. A chimney cleaner comprising a threaded rod, a spider mounted centrally thereon, springs secured centrally to opposite parts

of the spider and having brushes at their ends, a member threaded upon each end of the rod, an elongated member associated with each of the threaded members and disposed between corresponding end portions of the springs to effect lateral adjustment of the brushes, a bowed spring having its ends adjustably connected with the members mounted on opposite end portions of the threaded rod and movable therewith, an operating member, short flexible connections between the operating member and the upper ends of the brush carrying springs, and a flexible connection adjustably connecting the upper end of the bowed spring with the 70 75 80 said operating member.

In testimony whereof I affix my signature.
FERDINAND BUCHHOLTZ. [L. S.]
